SUBSTITUTED 9,10-ETHANOANTHRAZENE COMPOUNDS AND METHOD FOR THEIR PREPARATION

Karl Klager, Sacramento, Calif., assignor to Aerojet-General Corporation, Azusa, Calif., a corporation of Ohio

No Drawing. Filed Dec. 21, 1959, Ser. No. 861,137
14 Claims. (Cl. 260—465)

This application is a continuation-in-part of my copending application Serial No. 387,021, filed October 19, 1953, now abandoned, which was a continuation-in-part of my application Serial No. 235,569, filed July 6, 1951, now abandoned.

This invention relates to new compositions of matter and in particular to nitro-substituted endo anthracene compounds having the general formula

wherein R is an alkyl, halogen, ω -carboxyalkyl, ω -acyloxyalkyl, ω -carboalkoxyalkyl, cyanoalkyl, ω -formylalkyl, or alkylol radical.

The nitro-substituted endo anthracene compounds of this invention are valuable intermediates in the preparation of high explosives. Thus, when these compounds are heated they yield nitroolefin compounds having the general formula

wherein R is as defined above. This method of obtaining nitroolefin compounds from the novel endo anthracene compounds of the present invention is more fully disclosed in my copending application Serial No. 861,138, filed concurrently with this application.

The nitroolefins obtained from the compounds of this invention by the pyrolysis method of copending application Serial No. 861,138, in which R is an ω -acyloxyalkyl radical such as nitroallyl acetate, readily condense with nitro compounds having a labile hydrogen function, such as methyl 4,4-dinitrobutyrate, to form highly nitrated compounds, such as dimethyl 4,6,8,8-pentanitro-1,11-undecanedioate, useful as high explosives. A more complete description of this process can be found in my copending application Serial No. 636,839, now U.S. Patent No. 3,000,932, filed January 28, 1957. In addition, all of the nitroolefins obtained by pyrolysis from my novel compositions undergo an addition reaction with poly-nitro compounds having a labile hydrogen function, such as 2,2,4,4-tetrinitrobutyl acetate, to form highly nitrated compounds useful as high explosives. 2,2,4,4-tetrinitrobutyl acetate is disclosed in assignee's copending application Serial No. 617,667, filed October 22, 1956, now U.S. Patent No. 2,880,236. The addition reaction is conducted according to the method set forth in copending application Serial No. 636,839, now U.S. Patent No. 3,000,932.

The highly nitrated compounds obtained by the above-described methods are useful as high explosives and can be used in any conventional explosive missile, projectile, rocket, or the like, as the main explosive charge. An example of such a missile is disclosed in United States Patent 2,470,162, issued May 17, 1949. One way of using the high explosives of this invention in a device such as that disclosed in United States Patent 2,470,162 is to pack the crystalline explosive in powder form into the warhead of the missile. Alternatively, the crystals can be first

pelletized and then packed. A charge thus prepared is sufficiently insensitive to withstand the shock entailed on the ejection of a shell from a gun barrel or from a rocket launching tube under the pressure developed from ignition of a propellant charge, and can be caused to explode on operation of a nimpact- or time-fuse mechanism firing a detonating explosive such as lead azide or mercury fulminate.

Compounds of the present invention are conveniently prepared by condensing 11-nitro-9,10-ethanoanthracene with an alkyl halide, a halogen, an alkenoic acid ester, an alkenoic acid, an unsaturated nitrile, an alkanal, or an α,β -unsaturated aldehyde in the presence of an alkali metal or alkylene earth metal alcoholate. It is also within the scope of this invention to prepare my novel compositions by means of a two-step process. For example, 11-nitro-9,10-ethanoanthracene can first be reacted with an aldehyde such as acetaldehyde to yield an 11-alkylo-11-nitro-9,10-ethanoanthracene by the method described above and this composition can then be reacted with an anhydride such as acetic anhydride to produce, as a final product, an 11-carboalkoxyalkyl-11-nitro-9,10-ethanoanthracene within the scope of the general formula given above.

Specific examples of suitable reactants are ethyl iodide, butyl chloride, methyl iodide, Cl_2 , F_2 , ethyl acrylate, methyl methacrylate, propionaldehyde, acrylic acid, and acrylic aldehyde. These materials react with 11-nitro-9,10-ethanoanthracene to produce 11-ethyl-11-nitro-9,10-ethanoanthracene; 11-butyl-11-nitro-9,10-ethanoanthracene; 11-methyl-11-nitro-9,10-ethanoanthracene; 11-chloro-11-nitro-9,10-ethanoanthracene; 11-fluoro-11-nitro-9,10-ethanoanthracene; 11-(2-carboethoxyethyl)-11-nitro-9,10-ethanoanthracene; 11-(2-carbomethoxy-1-methylethyl)-11-nitro-9,10-ethanoanthracene; 11-(1-hydroxypropyl)-11-nitro-9,10-ethanoanthracene; 11-(2-carboxyethyl)-11-nitro-9,10-ethanoanthracene; and 11-(2-formylethyl)-11-nitro-9,10-ethanoanthracene, respectively.

The alcoholate used may be any of the alkali metal or alkaline earth metal alcoholates such as sodium methylate, calcium propionate, lithium ethylate, etc.

The following examples are supplied to more clearly illustrate my invention. It is to be understood, however, that these examples are supplied purely in an illustrative sense and are not intended to impose limitation upon the scope of the invention.

EXAMPLE I

Formation of 11-nitro-9,10-ethanoanthracene

One mole of nitroethylene is mixed with one mole of anthracene in the presence of o-dichlorobenzene. The mixture is heated for 45 minutes at approximately 150° C. The solvent is evaporated and the residue is dissolved in isopropyl ether. After cooling and recrystallization of the product from ethyl alcohol, 11-nitro-9,10-ethanoanthracene is obtained. This substance has a melting point between 113–114° C.

The following are examples of the manner in which 11-nitro-9,10-ethanoanthracene can be reacted to form various intermediates.

EXAMPLE II

Formation of 11-bromo-11-nitro-9,10-ethanoanthracene

One mole of 11-nitro-9,10-ethanoanthracene is dissolved in methanol and refluxed with one mole of sodium methylate, or other alcoholate of an alkali metal dissolved in the particular alcohol used to form the alcoholate, until reaction is complete. After evaporation of the solvent the residue is dissolved in water and a halogen such as bromine is added until there is an ex-

cess. If bromine is used it is added until the color does not bleach out. White crystals separate out which may be recrystallized from hexane. The compound formed in this manner is 11-bromo-11-nitro-9,10-ethanoanthracene and has a melting point of 128-129° C. The equation involved in this example is as follows:

Formation of 11-methylol-11-nitro-9,10-ethanoanthracene

One mole of 11-nitro-9,10-ethanoanthracene is converted into the acid-sodium salt by refluxing it until the reaction reaches completion with a solution of sodium methylate in methanol in which about one mole of sodium methylate is employed. The residue obtained after evaporation of the solvent is dissolved in water and one mole of formaldehyde is added. A viscous oil precipitates and the temperature rises somewhat. After two hours a solid material forms which may be filtered off and recrystallized from methanol and isopropyl ether. This compound is 11-methylol-11-nitro-9,10-ethanoanthracene, and has a melting point of 157°-158° C. The equation involved in this example is as follows:

Formation of 11-acetoxymethyl-11-nitro-9,10-ethanoanthracene

The 11-methylol-11-nitro-9,10-ethanoanthracene formed by the preceding procedure may be acetylated by treating the compound in a suitable container with acetic anhydride. The 11-acetoxymethyl-11-nitro-9,10-ethanoanthracene formed has a melting point of 103°-105° C. The reaction occurs in accordance with the following general formula:

Formation of 11-(2-cyanoethyl)-11-nitro-9,10-ethanoanthracene

A mixture of one mole of 11-nitro-9,10-ethanoanthracene is mixed with one mole of sodium methylate in

5
10

methanol and refluxed for 30 minutes. The solvent is evaporated and the residue dissolved in water. After the addition of one mole of acrylonitrile the mixture is stirred continuously for six hours at about 60° C. A yellow oil settles which solidifies when standing over night. The water is decanted. This oil is purified by several crystallizations from isopropyl ether and methanol. The compound thus obtained is 11-(2-cyanoethyl)-11-nitro-9,10-ethanoanthracene and has a melting point of 118-121° C. The reaction is illustrated by the equation

Formation of 11-(2-carbomethoxyethyl)-11-nitro-9,10-ethanoanthracene

One mole of 11-nitro-9,10-ethanoanthracene is treated with one mole of sodium methylate and dissolved in methanol and refluxed for 60 minutes. The solvent is evaporated and the solid suspended in water. One mole of methyl acrylate is added and the mixture is stirred for six hours at 55° C. White crystals are formed which can be recrystallized from acetic acid and methanol or isopropyl ether. The crystals are 11-(2-carbomethoxyethyl)-11-nitro-9,10-ethanoanthracene and exhibit a melting point of 155° C. The reaction is illustrated by the equation

50
55
60

The above reactions illustrate the manner in which the wide variety of substituted compounds of 11-nitro-9,10-ethanoanthracene can be obtained.

The 11-nitro-9,10-ethanoanthracene starting materials for the method of this invention are prepared by condensing nitroethylene with anthracene in accordance with the reaction scheme set forth below:

70
75
75

This reaction is more fully disclosed in my copending application Serial No. 387,022, filed October 19, 1953, now U.S. Patent No. 2,945,892.

The compounds of this invention, as noted above, may be pyrolysed to form the corresponding substituted nitroethylene derivatives which, as explained, are useful in the preparation of high explosives. In addition, the halogen substituted derivatives, such as 1-chloro-1-nitroethylene, find valuable use as pharmaceutical intermediates and also as intermediates in the preparation of wetting, detergent, and emulsifying agents as disclosed in U.S. Patent 2,510,281, issued June 6, 1950, and U.S. Patent 2,510,282 of the same date.

Reaction temperature is not critical to the novel method of this invention, the only significant effect of temperature variation being a variation in reaction rate.

I claim:

1. As compositions of matter, the substituted 9,10-ethanoanthracene compounds having the general formula

wherein R is a radical selected from the group consisting of halogen, lower ω -carboxyalkyl, and lower ω -formylalkyl radicals.

2. As compositions of matter, the substituted 9,10-ethanoanthracene compounds having the general formula

wherein R is a lower ω -carboxyalkyl radical.

3. As a composition of matter, 11-acetoxymethyl-11-nitro-9,10-ethanoanthracene.

4. As a composition of matter, 11-chloro-11-nitro-9,10-ethanoanthracene.

5. The method of preparing compounds having the general formula

wherein R is a lower alkyl radical, which comprises reacting 11-nitro-9,10-ethanoanthracene with a lower alkyl halide in the presence of an alkali metal alcoholate.

6. The method of preparing compounds having the general formula

wherein R is a lower alkylol radical which comprises reacting 11-nitro-9,10-ethanoanthracene with a lower alkanol in the presence of an alkaline earth metal alcoholate.

7. The method of preparing compounds having the general formula

wherein R is a lower ω -carboxyalkyl radical which comprises reacting 11-nitro-9,10-ethanoanthracene with a lower alkenoic acid in the presence of an alkali metal alcoholate.

8. The method of preparing compounds having the general formula

wherein R is a lower cyanoalkyl radical which comprises reacting 11-nitro-9,10-ethanoanthracene with a lower unsaturated nitrile in the presence of an alkali metal alcoholate.

9. The method of preparing compounds having the general formula

wherein R is a lower ω -carboalkoxyalkyl radical which comprises reacting 11-nitro-9,10-ethanoanthracene with a lower alkenoic acid ester in the presence of an alkali metal alcoholate.

10. The method of preparing 11-acetoxymethyl-11-nitro-9,10-ethanoanthracene which comprises reacting 11-nitro-9,10-ethanoanthracene with formaldehyde in the presence of sodium methylate to form 11-methylol-11-nitro-9,10-ethanoanthracene and reacting the 11-methylol-11-nitro-9,10-ethanoanthracene thus formed with acetic anhydride.

11. The method of preparing 11-bromo-11-nitro-9,10-ethanoanthracene which comprises reacting 11-nitro-9,10-ethanoanthracene with bromine in the presence of sodium methylate.

12. The method of preparing 11-(2-cyanoethyl)-11-nitro-9,10-ethanoanthracene which comprises reacting 11-nitro-9,10-ethanoanthracene with acrylonitrile in the presence of calcium propionate.

13. The method of preparing 11-(2-carbomethoxyethyl)-11-nitro-9,10-ethanoanthracene which comprises reacting 11-nitro-9,10-ethanoanthracene with methyl acrylate in the presence of lithium ethylate.

14. The method of preparing 11-substituted, 11-nitro-9,10-ethanoanthracene, which comprises reacting 11-nitro-9,10-ethanoanthracene with a compound selected from the group consisting of halogens, lower alkenoic acids and lower alpha-beta unsaturated aldehydes, in the presence of an alcoholate selected from the group consisting of alkali metal alcoholates and alkaline earth metal alcoholates.
